UNITED STATES PATENT OFFICE

114,997

DESIGN FOR A PACKAGED SEED DISPLAY STAND

Earle Everett Humphries, Los Angeles, Calif.

Application November 28, 1938, Serial No. 81,419

Term of patent 14 years

To all whom it may concern:

Be it known that I, Earle Everett Humphries, a citizen of the United States of America, residing at Los Angeles, in the county of Los Angeles and State of California, have invented a new, original, and ornamental Design for Packaged Seed Display Stands, of which the following is a specification, reference being had to the accompanying drawing, forming part thereof.

Figure 1 is a front elevational view of a packaged seed display stand showing my new design; and

Figure 2 is a side elevational view thereof.

I claim:

The ornamental design for a packaged seed display stand, as shown.

EARLE EVERETT HUMPHRIES.
